UNITED STATES PATENT OFFICE.

ANDREW N. TRUMPOWER, SR., OF HAGERSTOWN, MARYLAND.

COMBINATION RAILWAY-TIE AND RAIL-FASTENER.

1,377,942.

Specification of Letters Patent. Patented May 10, 1921.

Application filed April 26, 1920. Serial No. 376,651.

To all whom it may concern:

Be it known that I, ANDREW N. TRUMPOWER, Sr., a citizen of the United States, residing at Hagerstown, in the county of Washington and State of Maryland, have invented certain new and useful Improvements in a Combination Railway-Tie and Rail-Fastener, of which the following is a specification.

10 The invention relates to a metallic railway tie, and more particularly to the class of combined railway ties and rail fasteners.

The primary object of the invention is the provision of a railway tie of this character, 15 wherein the body of said tie is made from metal, preferably steel, and is reinforced at opposite sides thereof to render the tie strong, while in the top of the tie are seats for accommodating cleats which are adapted 20 to fasten the rails securely upon the tie, the cleats being of novel form and engaged with the top of the tie in a novel manner so as to avoid any possibility of the spreading of the rails laterally upon the tie, yet permitting 25 said rails to move longitudinally under expansion and contraction thereof, resultant from climatic changes.

Another object of the invention is the provision of a railway tie of this character, 30 wherein proper drainage is had from the seats for the cleats which serve to fasten rails upon the tie and thereby prevents water accumulating within the seats which would tend to rust the rails and seats and thereby in time 35 damage both the tie and rails, the cleats being fastened to the tie in a novel manner to firmly hold the rails secure upon the tie.

A further object of the invention is the provision of a railway tie of this character, 40 which is comparatively simple in construction, thoroughly reliable and efficient in its purpose, strong, durable and inexpensive to manufacture and install.

With these and other objects in view, the 45 invention consists in the features of construction, combination and arrangement of parts, as will be hereinafter fully described, illustrated in the accompanying drawing and pointed out in the claim hereunto appended.

50 In the accompanying drawing:

Figure 1 is a fragmentary top plan view of a pair of railway rails mounted upon a tie

and fastened thereto in accordance with the invention.

Fig. 2 is a side elevation of the railway tie showing the rails in vertical section.

Fig. 3 is a sectional view on the line 3—3 of Fig. 1.

Fig. 4 is a sectional view on the line 4—4 of Fig. 1.

Fig. 5 is a fragmentary top plan view of the railway tie showing the rail and cleats removed.

Fig. 6 is a perspective view of one of the cleats looking toward the bottom thereof.

Similar reference characters indicate corresponding parts throughout the several views in the drawing.

Referring to the drawing in detail:

The railway tie comprises a body A preferably made from metal, such as steel or the like, and is in the form of an I-shaped beam having the vertical central web 5 and top and bottom horizontal portions 6 and 7 respectively, while arranged on opposite sides 75 of the vertical web 5 between the top and bottom portions 6 and 7 are vertical reinforcing ribs constituting braces 8, which are detachably mounted in place upon said body and extend laterally from said web so that 80 their outer edges will be flush with the outer edges of the top and bottom portions 6 and 7 of the body of the tie, the said reinforcing braces 8 being preferably located immediately beneath the points where the track 85 rails rest upon the tie.

Formed in the top portion 6, centrally thereof, near opposite ends and disposed longitudinally of said tie, are channels or grooves 9, which are adapted to be bridged 90 by the rails 10 of a track when placed upon the top portion 6, of the tie and engageable with these grooves 9 are pairs of cleats 11, which are adapted to fasten the rails 10 upon the tie.

The cleat 11 of each pair is formed with a central ribbed bearing portion 12, having a flange engaging jaw 13 adapted to overhang and engage the base of the rail 10 to be fastened by the cleat, while on the bearing portion 12 of the latter, is a tongue 14, which is adapted to engage in the groove 9, in the top portion 6 of said tie so that the pair of cleats 11 will be locked in the groove

with which the tongues thereof engage to prevent displacement of the cleats 11 with respect to each other and thereby avoid the spreading of the rails 10 relative to each other when fastened upon the tie.

Passed through the bearing portions 12 of the cleats 11 are fasteners 15, which are tapped into the top portion 6 of the body of the tie and in this manner the said cleats 11 10 are secured to the tie for holding the rails 10 of the track fast upon the tie.

Formed in the top portion 6 of the body of the tie and leading from the grooves 9 are angular drain vents 16, extending downwardly and outside of the braces 8 which permit the draining of water from said grooves 9 in the top portion 6, should water, snow or the like accumulate therein, while engaged transversely in the web 5 of the 20 body A of the tie are bolts 17, which serve to fasten the braces 8 to the body A of the tie.

From the foregoing, it is thought that the construction and manner of use of the com-

bined railway tie and rail fastener will be 25 clearly understood and therefore a more extended explanation has been omitted.

What is claimed is:

A railway tie of the character described comprising a body formed with a vertical 30 web and horizontal top and bottom tapering portions extending therefrom, vertical reinforcing ribs permanently secured on opposite sides of the web and extending between the top and bottom tapering portions, the 35 said top portion being formed with a rectangular groove therein directly above the central web and at the points of engagement of the rails with the tie, slid able rail fastening means coöperating with the said 40 groove and secured to the top portion of the tie, the said rectangular groove having downward angular drainage passages communicating therewith extending on opposite sides of the vertical reinforcing ribs. 45

In testimony whereof, I affix my signature hereto.

ANDREW N. TRUMPOWER, Sr.
